UNITED STATES PATENT OFFICE.

WILLIAM G. FROST, OF INDIANAPOLIS, INDIANA.

RENEWABLE-FRONT WASHBOARD.

No. 888,155.

Specification of Letters Patent.

Patented May 19, 1908.

Application filed August 9, 1907. Serial No. 387,768.

To all whom it may concern:

Be it known that I, WILLIAM G. FROST, a citizen of the United States, residing at Indianapolis, in the county of Marion and State of Indiana, have invented certain new and useful Improvements in Renewable-Front Washboards; and I do declare the following to be a full, clear, and exact description of the invention, reference being had to the accompanying drawings, and to the letters and figures of reference marked thereon, which form a part of this specification.

This invention relates to the class of washboards in which the construction thereof admits of ready removal or insertion of the rubbing plate from the frame of the washboard, the invention having reference particularly to the portions of the frame in which the rubbing plate and its backboard are held, and means for removably holding them in the frame.

The object of the invention is to provide a simple and relatively inexpensive washboard having a well known type of rubber plate, a further object being to simplify and at the same time improve the construction of the frame and securing devices so that all will be compact and self-contained and adapted to be manipulated by the most inexperienced when it may be desired to renew the rubbing plate.

With the above-mentioned and minor objects in view the invention consists in a washboard comprising a frame having certain novel features of construction embracing guides in which a novel form of clamp bar is retained movably for securing the rubbing plate and backboard removably in the frame. And the invention consists further in the novel parts and combinations, and arrangements of parts as hereinafter particularly described and pointed out in the appended claims.

Referring to the drawings Figure 1 is a front perspective view of the improved washboard; Fig. 2, a rear perspective view; Fig. 3, a transverse vertical sectional view; Fig. 4, a transverse vertical sectional view of the frame without the clamp bar and the rubbing plate and backboard; Fig. 5, a horizontal sectional view of the frame on the line A A in Fig. 3; Fig. 6, a horizontal sectional view of the frame on the line B B in Fig. 3; Fig. 7, a fragmentary side view of the rubbing plate and the backboard; Fig. 8, a fragmentary end view of the backboard; Fig. 9,

a perspective view of the clamp-bar; Fig. 10, a fragmentary detail of a side bar showing the portion with which the clamp-bar is connected; and, Fig. 11, a longitudinal sectional view on the line C in Fig. 10.

Similar reference characters designate like elements or features of construction throughout the various figures of the drawings.

The improved washboard comprises two side bars *a* and *a'* which are substantially alike except that they are formed in reverse order so as to be right and left hand, and the rear middle portions are rabbeted out to an extent in length that is equal to the length of the rubbing plate, leaving shoulders *b* and *b'* at a suitable distance above their lower ends, and other shoulders *c* and *c'* at a suitable distance from the upper ends of the side bars, between which shoulders the rubbing plate is to extend, the side bars having shoulders *d* and *d'* extending along their forward edges and forming guide bearings against which the rubbing plate is to be held. These side bars are also rabbeted along their inner rear edges farther up beyond the shoulders *c* and *c'* to the upper ends of the side bars, leaving shoulders *e* and *e'* or seats against which the soap box bottom *f* is secured with its rear side flush with the rear sides of the side bars, and a head-board *g* is secured to the side bars and the soap box bottom.

A cross-bar *h* extends from one side bar to the other and has tenons *i* and *i'* which extend into the side bars, the latter being suitably recessed to receive them by being rabbeted somewhat beyond the shoulders *b* and *b'*, and the tenons are secured by means of nails *j* and *j'*. The cross-bar has a lip *k* extending upwardly and its extremity is in the same plane or flush with the shoulders *b* and *b'*, the cross-bar having a recess *l* between the lip and the bearing shoulders *d* and *d'*, the recess extending throughout the whole length of the cross-bar. The manner in which the soap box bottom is secured to the side bars insures great stiffness of the frame, which as will be apparent is augmented by the improved cross-bar *h* as above-described, so that a fixed cross-bar which is usually employed at the upper portion of a frame is not required.

A pair of guide ways *m* and *m'* are formed by mortising in the inner sides of the portions of the side bars *a* and *a'* adjacent to the shoulders *c* and *c'*, the guide ways being adjacent to the bearing shoulders *d* and *d'* and

extending above and preferably below the shoulders c and c' , so that portions of the guide ways are in the thicker portions of the side bars and extend into the portions of the side bars which have been rabbeted out to form the bearing shoulders d and d' , the guideways having broad guide faces n and n' extending from their upper ends down to the shoulders c and c' opposite to the bearing shoulders d and d' .

A novel form of clamp-bar o is provided which has guide wings p and p' projecting from its ends, and at its lower rear side it has a longitudinal lip q having a beveled front face q' , the wings being movable in the guideways m and m' and retained therein, the upper and lower ends of the guideways being stops for limiting the movements of the clamp-bar. The clamp-bar may be moved upwardly so that the lip q will clear the plane of the shoulders c and c' to receive the rubbing plate r and its backboard t , the rubbing plate being normally held against longitudinal movement by means of flanges s and s' formed on the upper and lower ends thereof which embrace the backboard the latter having cross pieces u and u' set into its ends for preventing warping of the backboard.

In practical use the clamp-bar o may be moved upwardly as shown in Fig. 4, and then the rubbing plate and the backboard together may be inserted in the frame against the bearing shoulders d and d' and in the recess l of the cross bar h , and then the clamp-bar o may be pushed down so that the lip q thereof will draw the backboard t tightly towards the bearing shoulders d and d' , thus securely holding the rubbing plate in the frame. A worn out rubbing plate

may quickly be removed as will be understood, by moving the clamp-bar upward so that the backboard and rubbing plate will be released and a new rubbing plate may be instantly inserted and secured, thus enabling the user to cheaply renew the perishable portion of the washboard.

Having thus described the invention, what is claimed as new is—

1. A washboard comprising a pair of side-bars having opposite guideways therein and bearing shoulders extending from the guideways, a rubbing-plate and back-board on the shoulders, and a clamp-bar having guide-wings extending into the guideways and retained therein, the wings being movable laterally and the clamp-bar having a lip provided with a beveled face engaging the back-board opposite to the shoulders.

2. A washboard comprising a pair of side-bars with longitudinal bearing shoulders thereon and a cross-bar with a lip extending opposite to the bearing shoulders, said side-bars having a pair of guideways extending longitudinally thereof and having guide-faces opposite to the planes of the bearing shoulders, a rubbing plate seated on the shoulders and under the lip of the cross-bar, a back-board seated against the rubbing plate, and a clamp-bar having a lip engaging the back-board and having also a pair of guide-wings extending into the guideways and slidably engaging the guide faces thereof.

In testimony whereof, I affix my signature in presence of two witnesses.

WILLIAM G. FROST.
